UNITED STATES PATENT OFFICE.

WINFIELD S. GILMORE, OF SORGHO, KENTUCKY.

PIPE-WRENCH.

SPECIFICATION forming part of Letters Patent No. 566,678, dated August 25, 1896.

Application filed February 23, 1895. Serial No. 539,427. (No model.)

To all whom it may concern:

Be it known that I, WINFIELD S. GILMORE, a citizen of the United States, residing at Sorgho, in the county of Daviess and State 5 of Kentucky, have invented a new and useful Pipe-Wrench, of which the following is a specification.

This invention relates to an improvement in pipe-wrenches, and refers particularly to 10 the subclass of chain-wrenches.

The object of the present invention is to simplify and improve the construction of wrenches of the character designated with a view to more thoroughly adapting them to engage 15 with and operate upon pipes of widely different diameters.

Other objects and advantages of the invention will appear in the course of the subjoined description.

20 The invention consists in an improved pipe-wrench embodying certain novel features and details of construction, whereby advantages in point of simplicity and adaptability are attained, as hereinafter fully described, 25 illustrated in the drawings, and finally pointed out in the claim.

In the accompanying drawings, Figure 1 is a perspective view of an improved pipe-wrench constructed in accordance with this 30 invention and shown applied in operative position upon a pipe. Fig. 2 is a side elevation of the same, illustrating the adaptability of the wrench to a pipe of relatively small diameter. Fig. 3 is also a side elevation of the 35 wrench, illustrating the manner in which the same may be opened preparatory to engaging the same with a pipe.

Similar numerals of reference designate corresponding parts in the several figures of the 40 drawings.

Referring to the drawings, 1 designates the handle of the wrench, which may be of any desired length, according to the desire of the manufacturer, the same having its outer operative end oppositely beveled, reduced in thickness, and expanded in width, and also provided upon the outer edge of such expanded end with a straight series of cogs 2, extending entirely across the head.

45 3 designates twin segmental plates, which are pivotally secured at their inner ends to one corner of the expanded end of the handle

1, and upon opposite sides thereof in such manner as to afford a space between said twin plates equal to or slightly greater than the 55 thickness of the end of the handle 1.

Between the outer ends of the twin plates 3 is pivotally secured one end of a segmental link 4, the opposite end thereof being formed with a groove or recess to receive the rounded 60 tongue or tenon of a similar segmental link 5. The opposite or outer end of the link 5 is also formed with a tongue or tenon fitting pivotally within a groove or recess in one end of another segmental link 6, which constitutes 65 the terminal link of the chain. The links 4, 5, and 6 are all of segmental form and are similar also in respect to their inner faces, which are each provided with ratchet-teeth, as shown. The links 5 and 6 differ, however, 70 from the link 4, in that they are provided upon their exterior faces with cogs 7, which, when the links are folded around a pipe, are adapted to be engaged by the cogs 2 on the operative extremity of the handle 1. It will 75 be noted further that the links 4, 5, and 6 are pivotally united in such manner and are of such thickness that both the terminal link 6 and the link 5, next adjacent thereto, may be passed between the twin segmental plates 80 3 when the device is applied to a pipe of small diameter, as shown in Fig. 2.

In operation the links are folded around and caused to embrace a pipe and the extremity of the terminal link 6 introduced between 85 the segmental plates 3 and advanced until the several links rest in contact with the exterior surface of the pipe, whereupon the handle 1 is vibrated in such manner as to cause the teeth or cogs thereof to engage with the cogs upon 90 the outer surface of the terminal link 6, or the adjacent link 5, as the case may be, which will have the effect of bringing the ratchet-teeth upon the inner faces of the several links into positive engagement with the pipe, thus 95 preventing all liability of the wrench slipping upon the pipe and obtaining a firm hold thereon, the force of which will be increased the further the handle 1 is vibrated. By pivoting the inner ends of the links 3 at one side 100 of the head and arranging the cogs 2 thereof in a straight series the handle-lever operates in two directions to collapse the links and clamp a pipe. The links 6 are drawn across

the head, and the handle by reason of its straight edge operates as a powerful lever to force the link 6 outward toward the link 4, and a powerful grip is thus effected. By reason of the particular construction described, the manner in which the links are jointed together, and the thickness thereof with relation to the space between the twin segmental plates 3 it will be seen that the wrench as a whole is adapted to be used in connection with pipes of various sizes, and is particularly adapted for pipes of relatively small diameter.

Having thus described the invention, what is claimed as new, and desired to be secured by Letters Patent, is—

A pipe-wrench comprising a hand-lever having a head beveled at opposite sides and provided with a straight outer transverse edge having a series of cogs or teeth extending entirely across the head, a pair of curved link-plates 3 having smooth inner and outer

edges arranged parallel with each other and pivoted at their inner ends to the said head at one end of a series of teeth, a curved link 4 having a smooth outer edge and provided at its inner edge with ratchet-teeth and pivoted at one end between the outer ends of the link-plates 3, and a series of curved links 6, pivotally connected together and with the link 4 provided at their inner edges with ratchet-teeth and having at their outer edges cogs or teeth to mesh with the cogs or teeth of the head, the latter being capable of drawing the links 6 across it and of forcing them outward from the pivot of the head, substantially as and for the purpose described.

Signed by me this 19th day of February, 1895.

W. S. GILMORE.
